ATTORNEYS.

UNITED STATES PATENT OFFICE.

SIDNEY J. ORNSTON, OF NEW YORK, N. Y.

BINDING-STRAP TIGHTENER.

1,353,973.

Specification of Letters Patent. Patented Sept. 28, 1920.

Application filed September 10, 1919. Serial No. 322,808.

To all whom it may concern:

Be it known that I, SIDNEY J. ORNSTON, a citizen of the United States, and a resident of the borough of Manhattan, city, county, 5 and State of New York, have invented certain new and useful Improvements in Binding-Strap Tighteners, of which the following is a specification.

My improvements relate to appliances for 10 drawing taut metallic binding straps, (either those formed of wire or those consisting of strips of greater width than thickness in cross section) around and upon packages of various kinds,—the overlapping ends of such 15 binding straps when thus tightly drawn together being then rigidly attached to each other while the band is still held taut by the tightening appliance, in a manner well known in a general way in the prior state of 20 the art.

The object of my invention is to afford a simple, inexpensive but effective strap 25 tightener of the character designated, adapted for use in connection with both metallic strip and wire binders, which can be expeditiously applied and actuated in a convenient manner, and which is at the same time of 30 strong and substantial structure, and well adapted to the varying requirements and exigencies of general use. To this end the invention consists in the specific construction, combination and arrangement of parts 35 described and claimed, a distinctive feature being the use of clamp blocks formed with non-rotatable screw studs of opposite pitch 40 in conjunction with a common rotatable clamping nut, in contra-distinction to the method heretofore in vogue of making the clamp blocks in the form of nuts actuated 45 by and upon a common reverse pitch screw shaft; the invention also including novel features in the structure of the clamp blocks themselves, and in the means for preserving their alinement etc., all as hereinafter fully set forth.

In the accompanying drawings,

Figure 1, is a plan of my new and improved strap tightening appliance, illustrating its use in connection with the opposite 50 site ends of a flat metallic strip binder;

Fig. 2, is a front elevation of the parts as shown in Fig. 1, the coupling nut being broken away in part;

Fig. 3, is an end view of the device as applied to a packing box, as in the two preceding figures;

Fig. 4, is a transverse section of one of the clamping jaws, taken upon plane of line 4—4, Fig. 1;

Fig. 5, is a sectional elevation taken upon 60 plane of line 5—5, Fig. 1;

Fig. 6, is a sectional perspective of the front portion of one of the clamp blocks, the block being broken away in part;

Fig. 7, is a perspective view of one of the 65 movable jaw plates, inverted;

Figs. 8 and 9, are views taken at right angles to each other, showing a modification in the means for actuating the coupling nut;

Fig. 10, is a view like unto Fig. 9, showing the nut released from the ratchet lever.

Fig. 11, is a view similar to Fig. 7, showing a modification.

The clamp blocks B, B, are held in coincidental alinement with relation to each other by means of an alinement rod A, upon which they are slidably mounted,—said rod A, extending through a bearing b, formed for it in the rear of each block.

The clamp blocks B, B, are likewise slidably connected with each other by means of the turn buckle nut N, which engages with non-rotatable screw studs S, S, protuberant from the adjacent sides of the said clamp blocks B, B. These screw studs are preferably, although not necessarily, rigid upon their respective blocks, but in any case they are non-rotatable thereon; and they are formed with relatively steep screw threads 85 of opposite pitch, the opposite ends of the turn buckle nut N, being correspondingly female screw threaded to engage with the threads on the adjacent screw studs S, S, as will be understood by reference more particularly to Fig. 5.

The turnbuckle nut N, may be rotated in either direction by means of a slip lever L, as provided for in Figs. 1, 2, 3 and 5, of the drawings,—said slip lever L, being slidable 100 in a transverse central bearing aperture n, formed for it through the body of the nut; or the turn buckle nut N, may be turned in one direction (that required to draw the clamp blocks toward each other) by a 105 ratchet lever L', as illustrated in the modi-

ification shown in Figs. 8, 9 and 10, in which case the body of the nut N , is formed with an annular ratchet n' , and the lever L' , is fulcrumed upon the nut N , and provided with a spring pawl l , mounted on a shaft fulcrumed on the lever and provided with a cam l' , for engagement with the spring l^2 , in such manner that the latter may be utilized either to hold the pawl in engagement 10 with the ratchet teeth, or to prevent its engagement therewith, as will be understood by reference to Figs. 9 and 10. Thus the ratchet lever L' , may be utilized to forcibly and positively draw a band taut, and after 15 the ends of the tightened band have been fastened together the pawl l , may be held disengaged from the nut ratchet n' , by means of the cam l' , and spring l^2 , as shown in Fig. 11, so that the nut may be turned by 20 direct hand contact to retract the clamp blocks, which, when relieved of the strain of the band, may be readily slid back without much exertion, whereas leverage of some kind is essential to turn the nut during the 25 operation of drawing the band taut.

Each clamp block B , is formed with a stationary gripping jaw b' , and with a movable gripping jaw b^2 , the latter preferably in the form of a floating plate controlled by 30 a pressure screw P , mounted on a fixed part b^3 , of the block and bearing against the upper side of said movable gripping plate b^2 . The pressure screw P , is used to force the movable jaw b^2 , down against the portion 35 of the end of the strap inserted between said movable jaw and the stationary jaw b' , and in this respect it acts against the resistance of the retractile springs r , r , which are interposed between the said fixed part b^3 , of 40 the block and the heads b^4 of studs b^5 attached to the movable jaw b^2 , and protuberant through holes formed for them in the fixed part b^3 , as shown more particularly in Figs. 4 and 6. Thus the springs r , r , tend 45 constantly to raise the gripping plate b^2 so that when the pressure screw is retracted, the said plate b^2 , will automatically release the portion of the strap against which it may have been clamped, thus facilitating 50 the insertion of a strap end between the gripping jaws and also the release thereof.

The opposed bearing faces of both clamping jaws b' , b^2 , are toothed, serrated or otherwise roughened to augment frictional 55 contact with a flat metal strap; and they are both preferably grooved coincidentally, as at b^x , to afford suitable bearings for a wire bail or strap, as shown more particularly in Figs. 6 and 7, so that my tightening device 60 is adapted for use in connection with wire straps as well as flat ribbon strips, both of which are in common use.

It is to be understood that the wire-groove b^x , may be formed in one or both of the gripping jaws b' , b^2 , as may be found most ex-

pedient, so that I do not limit my invention in this respect.

What I claim as my invention and desire to secure by Letters Patent is,

1. A strap tightening appliance of the character designated, comprising slidable clamp blocks formed with opposite pitch non-rotatable screw studs, a rotatable turn buckle nut engaging therewith, an alignment rod on which said clamp blocks are slidably mounted, and leverage means for actuating said turn buckle nut, each of said clamp blocks being formed with a stationary clamping jaw and a movable clamping jaw, and with a binding screw for forcing the movable jaw toward the stationary jaw for the purpose of positively gripping and holding the end of a binding strip between said jaws, together with spring tension means arranged to tend constantly to separate said movable clamping jaw from the stationary clamping jaw.

2. A strap tightening appliance of the character designated, comprising slidable clamp blocks formed with opposite pitch non-rotatable screw studs, a rotatable turn buckle nut engaging therewith, an alignment rod on which said clamp blocks are slidably mounted, and leverage means for actuating said turn buckle nut, each of said clamp blocks being formed with a stationary clamping jaw and a movable clamping jaw, and with a binding screw for forcing the movable jaw toward the stationary jaw for the purpose of positively gripping and holding the end of a binding strip between said jaws, and the opposed surfaces of the said clamping jaws being roughened for contact with a flat metal binding strip.

3. A strap tightening appliance of the character designated, comprising slidable clamp blocks formed with opposite pitch non-rotatable screw studs, a rotatable turn buckle nut engaging therewith, an alignment rod on which said clamp blocks are slidably mounted, and leverage means for actuating said turn buckle nut, each of said clamp blocks being formed with a stationary clamping jaw and a movable clamping jaw, and with a binding screw for forcing the movable jaw toward the stationary jaw for the purpose of positively gripping and holding the end of a binding strip between said jaws, one or both opposed faces of the said clamping jaws being grooved for contacting with a round wire binding strip.

4. A strap tightening appliance of the character designated, comprising slidable clamp blocks formed with opposite pitch non-rotatable screw studs, a rotatable turn buckle nut engaging therewith, an alignment rod on which said clamp blocks are slidably mounted, and leverage means for actuating said turn buckle nut, each of said clamp blocks being formed with a station-

ary clamping jaw and a movable clamping jaw, and with a binding screw for forcing the movable jaw toward the stationary jaw for the purpose of positively gripping and holding the end of a binding strip between said jaws, and the opposed faces of the said clamping jaws being coincidentally grooved

for contacting with a round wire binding strap, and also roughened for contact with a flat metal binding strap.
